GRINDING MACHINE

Clement Booth, Cincinnati, Ohio, assignor to Cincinnati Grinders Incorporated, a corporation of Ohio

Original application May 20, 1927, Serial No. 192,878. Divided and this application December 24, 1934, Serial No. 759,087

8 Claims. (Cl. 125—11)

This invention relates to centerless grinding machines and more particularly to the truing of the wheels thereof.

This application is a division of my application 5 Serial No. 192,878, filed May 20, 1927, entitled "Grinding machine", patented December 25, 1934, as Patent No. 1,985,237.

One of the objects of this invention is to provide a simple, practical and efficient apparatus 10 for truing the wheels of a centerless grinding machine. Another object is to provide an apparatus of the above-mentioned nature capable of wide range of use and of accurate action and operation. Another object is to provide a grinding 15 machine of the above-mentioned nature which is convenient to operate and to true the wheels quickly and accurately to meet the conditions of practical use. Other objects will be in part obvious or in part pointed out hereinafter.

20 The invention accordingly consists in the features of construction, combinations of elements, and arrangements of parts as will be exemplified in the structure to be hereinafter described and the scope of the application of which will be indicated in the following claims.

25 In the accompanying drawings in which is shown one of the various possible embodiments of this invention,

Figure 1 is a vertical longitudinal sectional view of the grinding machine, certain parts being 30 omitted;

Figure 2 is a top plan view with certain parts broken away;

Figure 3 is a front elevation on a larger scale, 35 as it would be seen from the front in Figure 2, of a portion of the machine showing the mechanism for use in connection with truing the wheels, and

Figure 4 is a vertical sectional view as seen 40 along the line 4—4 of Figure 3, and

Figure 5 is a fragmentary diagrammatic top plan view on a reduced scale showing the relationship of one of the grinding wheels, the truing wheel therefor, and the gauge bar.

45 Similar reference characters refer to similar parts throughout the several views of the drawings.

For complete details of the grinding machine per se, reference is made to my above-mentioned 50 patent.

Referring now to Figures 1 and 2, the grinding machine comprises generally a frame 10, slidably supporting a pair of carriages 11 and 12, which 55 rotatably mount a grinding wheel 16 and a regulating wheel 20, these wheels having disposed

therebetween a work support 21, adapted to support a work piece 241 (Figure 3). Carriages 11 and 12 (Figure 1) are manually movable toward and away from one another by means of hand wheels 36 and 22 respectively, there being also 5 provided a hydraulic mechanism generally indicated at 28 for reciprocating carriage 11 and regulating wheel 20. Thus wheels 16 and 20, and work support 21, comprise a work receiving 10 throat the size of which is readily variable by movement of the carriages to receive work of different diameters.

Wheels 16 and 20 (Figure 3) preferably rotate in the same direction so that the portions thereof of contacting opposite sides of work piece 241 move in opposite directions as indicated by the arrows in Figure 1. Regulating wheel 20 rotates at a much slower speed than grinding wheel 16, and its axis is inclined with respect to the axis of work piece 241 and wheel 16 so that a feeding 20 component is exerted upon the work piece to effect feeding thereof along work support 21 and across the abrasive periphery of grinding wheel 16, thus to feed the work piece through the above-noted throat, all as is described in detail in my 25 above-noted patent.

Carriages 11 and 12 mount respectively truing tools 218 and 217 which are automatically reciprocable in hydraulic cylinders 219 and 220 respectively, suitable valve and pipe connections 221 and 223 being provided respectively for each of the cylinders. Truing tools 218 and 217 are respectively provided with diamond points 216 and 215 which, when moved across the surfaces of wheels 20 and 16 respectively, dress the surfaces 30 of these wheels. It should be noted in this connection that when the wheels are being trued, and particularly in the case of the regulating wheel, 35 it is important that the path of travel of the truing tool across the wheel surface be properly related to the line of contact between the wheel and the work. For example, when the axis of the regulating wheel is inclined, as pointed out above with respect to the path of movement of the work, the chief function of the truing is to dress 40 the wheels' surfaces so that they present to each other properly related lines along which the work is to contact with the wheels. Particularly in centerless grinding machines, it is advantageous in many cases to "grind above centers" and in other cases to "grind below centers" and I have 45 illustratively shown in Figure 1 a grinding machine set up to grind above centers.

In a machine in which the wheels are arranged as shown in Figure 1 of the drawings, best re- 50 55

sults in grinding cylindrical work are had when the lines of contact between the work and the wheels are above the center line of the two wheels, as is more clearly shown in Figure 3. When the 5 grinding wheels and work are so arranged, it is quite important that the truing tool engage the wheel it is dressing along a line in the plane of the lines of contact between the wheels and the work. The importance of this feature lies in the 10 fact that, particularly with respect to the regulating wheel whose axis as noted above is inclined, dressing of the regulating wheel by the truing wheel results in a slight concavity in the peripheral surface of the wheel. If the line of contact 15 between the truing tool and the regulating wheel is either above or below the proper plane of engagement, then the degree of concavity in the regulating wheel will vary from the proper value and the wheel can not properly engage the work 20 piece to grind it accurately.

For example, with reference to Figure 3, the peripheral surface of regulating wheel 20, if dressed by passing truing tool 216 thereover along line 225, would be materially different from the 25 surface resulting from passing the truing tool thereover along line 226. The configuration of the former surface would be incorrect and could not accurately grind work piece 241.

Still referring to Figure 3, truing tool 216 is 30 shown mounted to operate upon the surface of regulating wheel 20 on the side thereof opposite to work piece 241. This is of substantial advantage over passing the truing tool between the 35 wheels, since it is not necessary to interfere with the setting of the work support or other adjustments in order to true the wheels.

The truing tool 216 is mounted in a bracket 227 which is carried by and is vertically adjustable in the slide 218 and which may be locked 40 in the position to which it is adjusted by means of a set screw 228. Secured to the guard 229 about the wheels is a bracket 230 having an outwardly projecting arm 231 (see also Figure 4) which provides at its outer end an elongated bearing 232 in which is supported a rod 233. This rod 233 is squared except for the portion 45 233a thereof which is supported in the bearing 232. A set screw 234 is provided for fixing the position of the rod 233 in its bearing. Slidably 50 mounted upon the squared rod 233 is a bracket 235 having a depending portion 236 in which is slidably supported a pin 237 (see also Figure 4). The left-hand end of the rod 233 extends in front 55 of and is spaced from the surface of the truing tool supporting bracket 227 and the front surface of regulating wheel 20.

The bracket 230 is vertically adjustable upon 60 the guard 228. Preferably, its under-surface is grooved and mates with a guiding projection 238 on the guard, and it may be locked in the vertical position to which it is adjusted by means of a clamping bolt 239 passing through a vertical slot 240 therein. The use of this construction is as follows: A work piece such as 241 of 65 the size to be ground is placed in the grinding throat and in engagement with the wheel surfaces. The point 237 is then slid inwardly (see Figure 4), the bracket 236 is slid along the squared rod 233 and the bracket 230 is adjusted vertically until the point 237a (Figure 4) of the pointer coincides with the point 226 (Figure 3) which marks the line of contact between the regulating wheel and the work. The rod 233 is parallel to the center line 225. The vertical distance 70 between the center of the pointer 237 and

the rod 233, for example, the lower edge of the rod, is a fixed distance. The truing tool supporting bracket 227 is now adjusted vertically in the slide 218, by loosening the set screw 228, until the vertical distance between the truing point and the lower edge of the bar or rod 233 is exactly equal to the fixed distance between the center of the pointer 237 and the lower edge of the rod. This fixed distance is indicated by appropriate markings upon the surface of the 10 bracket 227 in order to facilitate this adjustment. In this manner, the proper vertical adjustment of the truing tool is made with the greatest convenience.

Accordingly, when the truing tool 216 is subsequently traversed across the face of the regulating wheel 20, by the hydraulically-actuated mechanism 218-219 (Figures 1 and 2), the latter causing the truing tool 216 to move in a straight line parallel to the axis of the work piece 241 (Figure 3), the tilted regulating wheel 20 has its operative peripheral surface thereby slightly concaved to present at 226 (Figure 3) a straight line across its surface with which the work piece 241 contacts or in which the regulating wheel 20 and work piece 241 are tangent as the regulating wheel, and slowly rotating in the direction of the arrow, rotates the work piece 241 as the grinding wheel 16, juxtaposed to the regulating wheel, grinds the work piece. As the tilted regulating wheel feeds the work in an axial direction along the work support 21 (in a direction toward the member 129 in Figure 2), therefore, a true straight line contact between regulating wheel and work piece is maintained during this movement, it being understood that the line of contact of the work piece 241 (Figure 3) with the work support 21 and the line of contact between the work piece 241 and the grinding wheel 16 are parallel to each other 30 and parallel to the line of traversing movement of the truing tool 216 as the path of movement of the latter is determined by its supporting and moving mechanism 218-219 (Figures 1 and 2).

Should a different diameter of work have to 45 be ground, so that this line of contact of the regulating wheel with the work is lower or higher than that illustratively above assumed or is lower or higher than the center line 225 (Figure 3), the above-outlined procedure is again 50 gone through. The differently diametered work piece is put in place between the two wheels, the bracket 230 (Figures 3 and 4) is correspondingly readjusted so that the pointed end 237a of the index pointer or pin 237 is at a height to 55 correspond to the new line of tangency, whereupon the truing tool bracket or support 227 (Figure 3) is shifted vertically relative to its slide 218 to correspond and hence to bring its point to the same distance below the rod or base 233 60 as is the spacing from the latter of the index point or pin 237a.

It will be noted that, referring to Figure 3, and as already noted above, the bar 233 is of 65 sufficient length to extend beyond the left-hand end or side of the regulating wheel 20 and virtually to extend across the path of movement of the bracket 227 itself, assuming that the latter is capable of movement toward the observer viewing Figure 3 beyond the outermost edge of the wheel 20. Because of this extension of the rod 233, the above-mentioned markings or graduations 300 (Figure 3) on the surface of the bracket 227 may, if desired, be used to set the vertical position of the bracket 227 by reference 70 to 75

to a horizontal edge, such as the lower horizontal face, of the bar 233, or, of course, they may be used to set the bracket 227 by reference to a fixed mark on the main slide or support 5 218.

I may, however, as will be clear from what has earlier above been set forth as well as from a consideration of Figure 3, loosen up the set screw 234 that fixes the slidable bracket 236 in position 10 relative thereto, and, after having raised or lowered the bracket 230 to cause the point 237* to coincide with the new point or line of contact between regulating wheel and work piece, slide the bracket 236 to the left (Figure 3) along the rod 15 233 and thereby bring the pointed end 237* of the pin 237 to rest exactly at the periphery of the regulating wheel 28 but to the left of its axis, and then adjust the vertical position of the bracket 237 and hence of the truing point or tool 216 so 20 that the latter coincides in vertical position with the point 237*.

Where I utilize graduations or markings 300 on the tool bracket 227, as above pointed out, I prefer, however, to provide graduations on the guiding projection 238 similar graduations or markings 301 which may be proportioned, numbered, or otherwise appropriately related to the markings 300 on the truing tool bracket 227; hence, I may, by the markings 301, read off the change in vertical position that is given the bracket 230—231 and hence the bar 233 and hence the pointer 237 for any differently diametered work for which the wheels are to be conditioned or trued; and then by means of the graduations or markings 300 on 35 the tool bracket 227, make an identical change in vertical position of the bracket 227 and of the diamond point or truing tool 216.

It will thus be seen that there has been provided in this invention a method and apparatus 40 in which the objects of the invention, together with many thoroughly practical advantages, are successfully achieved. Appropriate and proper conditioning of the tilted regulating wheel will be seen to be quickly and easily brought about in 45 spite of the great range of varied conditions met with in practice, and, moreover, the correct conditioning of the tilted regulating wheel will be seen to be achieved in a simple, speedy and fool-proof manner and free from tedious and time-consuming operations.

As many possible embodiments may be made of the above invention and as many changes might be made in the embodiment above set forth, it is to be understood that all matter hereinbefore set forth, or shown in the accompanying drawings, is to be interpreted as illustrative and not in a limiting sense.

I claim:

1. The combination with a grinding machine 60 having an abrasive wheel, means for supporting work in operative relation to said wheel, a member mounted for movement transversely of the operative surface of said wheel on the side thereof opposite from said work support, and a truing 65 tool carried by said member and adjustable in position substantially transversely of the direction of movement of said member, of means for gaging the line of contact of said tool and said wheel with respect to the line of contact between 70 said work and said wheel comprising a member extending transversely of the axis of said wheel and passing adjacent to said truing tool and adjacent to said work support, means mounting said member for adjustment in position in a direction 75 transversely of said two lines, and a pointer car-

ried by said member adapted to be brought by adjustment of said member into registry with one of said lines of contact.

2. The combination with a grinding machine 5 having an abrasive wheel, means for supporting work in operative relation to said wheel, a member mounted for movement transversely of the operative surface of said wheel on the side thereof opposite from said work support, and a truing tool carried by said member and adjustable in position substantially transversely of the direction of movement of said member, of means for gaging the line of contact of said tool and said wheel with respect to the line of contact between 10 said work and said wheel comprising a member extending transversely of the axis of said wheel and passing adjacent to said truing tool and adjacent to said work support, means mounting said member for adjustment in position in a direction transversely of said two lines, and a pointer facing inwardly toward said wheel and mounted upon said member for adjustment in position lengthwise thereof.

3. The combination with a grinding machine 25 having an abrasive wheel, means for supporting work in operative relation to said wheel, a member mounted for movement transversely of the operative surface of said wheel on the side thereof opposite from said work support, and a truing tool carried by said member and adjustable in position substantially transversely of the direction of movement of said member, of means for gaging the line of contact of said tool and said wheel with respect to the line of contact between 30 said work and said wheel comprising a member extending transversely of the axis of said wheel and passing adjacent to said truing tool and adjacent to said work support, means mounting said member for adjustment in position in a direction transversely of said two lines, a bracket mounted upon said 35 member for adjustment in position lengthwise thereof, and a pointer carried in said bracket facing toward said wheel and slidably in said bracket toward and away from said wheel.

4. The combination with a grinding machine 45 having means forming a grinding throat comprising a grinding wheel, a work support, and a regulating wheel whose axis is in tilted relation to the axis of a work piece that rests on said work support, an elongated device extending 50 across the end face of said regulating wheel and extending parallel to the line joining the centers of said two wheels, a member slidably along said elongated device and having a part capable of being positioned at the same vertical displacement from said line as is the point of contact between the work piece and said regulating wheel, a truing tool, and means whereby the truing tool may be set to operate at that peripheral portion of the regulating wheel juxtaposed from 55 said grinding throat at a position displaced from said line by the same amount as indicated by said part, said part being slidable along said device for coaction with said truing tool whereby the latter may be set.

5. The combination with a grinding machine 60 having means forming a grinding throat comprising a grinding wheel, a work support, and a regulating wheel whose axis is in tilted relation 65 to the axis of a work piece that rests on said work support, of a truing tool operative upon said regulating wheel in a region of the latter remote from said grinding throat and having a path of movement parallel to the axis of a work piece supported in the latter, said truing tool 70

65

70

75

- being vertically adjustable, means movably mounted on said machine for determining the vertical displacement of the line of contact between said work piece and said regulating wheel relative to a suitable datum, and means operatively connected to said machine and said truing tool responsive to the operation of said movable means for indicating the vertical adjustment to be given said truing tool.
6. The combination with a grinding machine having an abrasive wheel with means for supporting work in operative relation to said wheel and a truing tool carried by a member mounted for movement across the operative surface of said abrasive wheel on the side thereof opposite from said work-supporting means, of an elongated member supported adjacent said abrasive wheel and extending from the side thereof adjacent said work-supporting means to the side thereof adjacent said truing tool, a device slidably carried by said elongated member and positionable to either of said sides when slid along said elongated member, said device having a pointer, means for adjustably positioning said pointer in a direction transverse to the direction of sliding movement of said device along said elongated member, whereby said pointer may be positioned in the plane of the point of contact between said abrasive wheel and a work piece on said work-supporting means, said device, after said adjustment, being slideable along said elongated member to said other side of said wheel adjacent said truing tool, thereby positioning said pointer adjacent the latter, and means for adjusting the position of the truing tool with respect to said pointer.
7. The combination with a grinding machine having an abrasive wheel with a work support in operative relation thereto, and a truing tool carried by a member mounted for movement across the operative surface of said abrasive wheel on the side thereof opposite said work support, of a bracket, means movably attaching said bracket to a portion of said grinding machine, said bracket including a supporting part extending outwardly from said machine to a point spaced from the front surface of said abrasive wheel, an elongated member secured in said part, an element slidably carried by said elongated member and positionable to either side of said abrasive wheel when slid along said elongated member, said element including a pointer, means for adjustably positioning said pointer in a direction transverse to the direction of sliding movement of said element along said elongated member, whereby said pointer may be positioned in the plane of the point of contact between said abrasive wheel and a work piece on said work support, and means for adjusting the position of said truing tool and hence its path of travel across the said side of said abrasive wheel in accordance with the adjustment given said pointer.
7. The combination with a grinding machine having an abrasive wheel with means for supporting work in operative relation to said wheel and a truing tool carried by a member mounted for movement across the operative surface of said abrasive wheel on the side thereof opposite from said work-supporting means, of an elongated member supported adjacent said abrasive wheel and extending from the side thereof adjacent said work-supporting means to the side thereof adjacent said truing tool, a device slidably car-

ried by said elongated member and positionable to either of said sides when slid along said elongated member, said device having a pointer, means for adjustably positioning said pointer in a direction transverse to the direction of sliding movement of said device along said elongated member, whereby said pointer may be positioned in the plane of the point of contact between said abrasive wheel and a work piece on said work-supporting means, said device, after said adjustment, being slideable along said elongated member to said other side of said wheel adjacent said truing tool, thereby positioning said pointer adjacent the latter, and means for adjusting the position of the truing tool with respect to said pointer.

8. The combination with a grinding machine having an abrasive wheel with a work support in operative relation thereto, and a truing tool carried by a member mounted for movement across the operative surface of said abrasive wheel on the side thereof opposite said work support, of a bracket, means movably attaching said bracket to a portion of said grinding machine, said bracket including a supporting part extending outwardly from said machine to a point spaced from the front surface of said abrasive wheel, an elongated member secured in said part, an element slidably carried by said elongated member and positionable to either side of said abrasive wheel when slid along said elongated member, said element including a pointer, means for adjustably positioning said pointer in a direction transverse to the direction of sliding movement of said element along said elongated member, whereby said pointer may be positioned in the plane of the point of contact between said abrasive wheel and a work piece on said work support, and means for adjusting the position of said truing tool and hence its path of travel across the said side of said abrasive wheel in accordance with the adjustment given said pointer.

CLEMENT BOOTH. 45
